UNITED STATES PATENT OFFICE.

EDWARD NEY, OF NEW YORK, N. Y.

DESIGN FOR A JAR FOR URNS.

SPECIFICATION forming part of Design No. 34,667, dated June 18, 1901.

Application filed May 20, 1901. Serial No. 61,201. Term of patent 14 years.

To all whom it may concern:

Be it known that I, EDWARD NEY, a citizen of the United States, residing at 183 Thompson street, New York, in the county of New York and State of New York, have invented and produced a new and original Design for Jars for Urns, of which the following is a specification, reference being had to the accompanying drawings, forming a part thereof.

Figure 1 is an elevation of a jar for urns embodying my new design. Fig. 2 is a plan view of the same. Fig. 3 is a longitudinal section.

As shown in the accompanying drawings, the leading or material feature of my design consists of a slightly-tapered "cylindrical" body portion 1, a rounded bottom 2, flattened

near the center, as at 3, and having centrally therein a hole or opening 4 and a circumferential enlargement 5, forming a shoulder 5^x 20 on the outside and a ledge 5^{xx} on the inner side, provided with an opening or hole 5', and a bead or flange 6, with a groove 7 on its under side, near the top thereof.

Having thus fully described my design, what I claim as new, and desire to secure by Letters Patent, is—

The design for a jar for urns as herein shown and described.

EDWARD NEY.
